UNITED STATES PATENT OFFICE

2,366,540

AIR CONDITIONER

Norman E. MacLean, San Francisco, Calif.

Application May 11, 1942, Serial No. 442,464

2 Claims. (Cl. 183—4.8)

The present invention relates to air conditioners, and particularly to an air conditioning unit which is compact and arranged in a relatively small, vertical, cylindrical container, so that it may be supported for operation within a ventilator pipe or king post on ship board for conditioning the air in one or more of the ship's holds.

Moisture in the hold of a ship, which results largely from condensation when the ship moves through belts of different temperature and climatic conditions, is dangerous and often destructive to many kinds of cargoes. It is, therefore, desirable to employ means for reducing the moisture content of the air in ships' holds, thus eliminating condensation and destructive dampness.

A major consideration on cargo ships is space for cargo, and all space occupied by necessary equipment of course reduces the cargo space, while ventilator cowls and their shafts or pipes are now sometimes omitted in ship construction. The king post, which is of hollow steel construction, is always present and extends above the main deck and down through the holds. Both ventilator pipes and king posts present vertical, cylindrical spaces usually free of all equipment and conveniently arranged for the disposition of equipment for conditioning the air in the holds. These pipes and posts are usually approximately thirty inches in diameter, and are necessarily sealed off if efficient conditioning of the air in the hold is to be accomplished.

It is the object of the present invention to provide an air conditioning unit capable of controlling humidity and other factors in the air of ships' holds, and adapted to be contained and operated within a ventilator pipe or king post.

A further object of the invention is the provision of an efficient and compact unit having means for supporting a large quantity of a hygroscopic agent with a relatively large surface area of the agent exposed to a circulating air stream and having means for automatically replenishing the air to said area and efficiently disposing of the moisture which is taken from the air by the agent.

Further objects and advantages of the invention are made apparent in the following specification, wherein reference is made to the accompanying drawing, which illustrates a preferred form of the invention.

In the drawing—

Figure 1 is a vertical sectional view through an air conditioning unit, embodying the present invention, and

Figure 2 is a sectional view taken on the line II—II of Figure 1.

As shown in the drawing, the present invention comprises a vertical, cylindrical container 10 which may be made of relatively light sheet metal or the like, and the upper end of which is preferably closed by a cover 11. A blower 12 is disposed in the container adjacent its upper end and is operated by a motor 13. An intake duct 14 communicates with the inlet 15 of the blower so that air which enters the container 10 at the lower right-hand portion thereof, as viewed in Figure 1, is drawn across the container through a chamber adjacent the lower end which contains a hygroscopic agent, as will presently be described, and then upwardly through the duct 14 and into the blower. Relatively dry air is, therefore, discharged by the blower through a rectangular duct 16, which extends downwardly and projects outwardly from the bottom of the container 10, where it may be divided into two ducts, as shown, or into more, depending upon the number of compartments in the hold of the ship to which it is desired to supply dry air. The entire assembly is such that it may conveniently be lowered into a ventilator pipe or king post, where it may be supported at a desired elevation by any suitable brackets or cross braces, not shown, provided in the pipe or king post for that purpose. The side wall of the container 10 is provided with an opening covered by a removable plate 17, which is secured in place as by means of bolts 18, and which may be gasketed, as indicated at 19. This plate will register when the unit is in position with an opening in the side of the king post or ventilator pipe, which is similarly covered to permit access to the motor 13 for the purpose of inspection or repair, and also to permit access to an opening normally closed by a cover 20, which opening is formed in a horizontal partition 21 which separates the motor and blower from the lower portion of the container and forms a top wall for a chamber 22 adapted to contain a supply of a hygroscopic agent, such, for example, as calcium chloride, in loose, granular, or crystalline form. The bottom of this chamber 22 is formed by a horizontal partition 23, which is best shown in Figure 2, which has rows of large perforations for the reception of cone-shaped receptacles of screen or other reticulated material which depend into the de-humidifying chamber through which air is drawn by the fans 15 in the manner indicated by arrows on the drawing. Conical receptacles for the de-hu-

midifying agent are of two shapes arranged in alternate rows, which rows are closely spaced and staggered in the manner illustrated in Figure 2. The first shape, being that shown at 24, consists of a cone of screen with its apex extending downwardly and having a collar of imperforate material 25 adjacent its upper end and a flange 26 projecting outwardly from its top edge to form a support by means of which the cone is suspended when it is inserted through the perforation provided for in the partition 23. The second type of cone is that illustrated at 27, the walls of which diverge downwardly and turn inwardly to form an apex at its lower end. This type of cone also has an imperforate collar 28 adjacent its upper end, and a flange 29 by which it is supported in the same manner as the cone 24. The perforate cones arranged and supported in this manner serve several useful functions in connection with the exposure to the air of the hygroscopic agent which they contain. Where calcium chloride or a similar agent is employed, the surface against which the moist air impinges takes on moisture and becomes caked or hardened so that it will not flow readily in the manner of the original loose, granular material. At the same time that it cakes or hardens, its bulk is reduced by reason of the fact that the moisture collecting upon it drains and carries with it some of the agent in the form of a briny residue. When the agent cakes and is reduced in size in the cone-like containers, it gravitates freely toward the bottom of the container, thus affording space at the top of the container for the introduction of a further supply. A supply is contained in the chamber 22 through which it has been introduced in the manner described and wherein it is preserved in its granular form so that it flows freely into the reticulated cones. The collars 25 and 28 at the upper ends of the cones are provided for the purpose of insuring against the granular hygroscopic agent in the chamber 22 becoming moist and, therefore, caked to the extent that it will not feed freely into the upper ends of the cones, as the agent contained by the cones recedes downwardly. Furthermore, as alternate rows of the cones are inverted and staggered, the air being drawn in a horizontal path through the chamber which is occupied by the cones is caused repeatedly to impinge directly against the cones, which present an unusually large surface area of the hygroscopic agent, thus insuring rapid exchange of moisture. As the bottoms of all of the cones terminate in a point or apex, free dripping of the residual brine is encouraged and a drip pan 30 is provided to receive this brine which may be conducted away through a conduit 31 and disposed of in any convenient manner. The drip pan 30 also serves as a bottom wall for the chamber which contains the hygroscopic agent, closing all except the passage at the right-hand side through which the air is drawn.

In order to steady the cones to prevent their swinging in the event of a ship's being tossed on a rough sea, a plate 32 is preferably provided adjacent the top of the drip pan 30. This plate

is rigidly secured to the drip pan and is provided with perforations, as shown, through which the lowermost ends of the cones extend.

Another advantage of the arrangement of the cones herein disclosed is that the air which passes over them is effectively filtered or scrubbed by its contact with the moist surface of the hygroscopic agent. Furthermore, as free drainage of the moisture collected by this agent is provided for, any dust, or other impurities which are taken from the air in this manner, is carried off by the briny residue which drips into the pan 30.

While the essential elements of the air conditioning unit are shown for purposes of illustrating the present invention, it is, of course, to be understood that it may be automatically controlled by instruments which measure the moisture content in the air and actuate a switch which controls the electric motor, all of which may be done in many conventional ways, and forms no part of the present invention.

Ordinarily, a ship is equipped with two king posts or ventilator pipes for each hold, though in some cases there may be more. In any event, these are sealed off so that the present unit produces a continuous circulation of air through a closed circuit unless it is desired to provide some opening for the admission of a limited amount of fresh air.

While the present invention has been described in its application to the conditioning of air on board ships, its use is not thus specifically restricted, as it is readily applicable to the conditioning of air in any closed area, and provides a relatively small, portable and efficient unit having many advantages over other devices constructed for this purpose. The unit, as disclosed, is also applicable to the conditioning of air otherwise than by reducing its humidity, as there is ample space provided—for example, in the chamber 14—for the introduction of heating, cooling, deodorizing and other mechanisms or agents which may act upon the air either with or without the de-humidifying unit.

Having thus described my invention, what I claim and desire to secure by Letters Patent is:

1. In an air conditioning unit having a dehumidifying chamber through which air to be conditioned is passed, a plurality of reticulated baskets adapted to contain a hygroscopic agent, said baskets being vertically positioned and arranged in staggered rows, the baskets of alternate rows being tapered toward their bottom ends, and the other baskets being tapered toward their upper ends.

2. In an air conditioning unit having a dehumidifying chamber through which air to be conditioned is passed, a plurality of reticulated baskets adapted to contain a hygroscopic agent, said baskets being vertically positioned and arranged in staggered rows, the baskets in alternate rows being substantially conical in shape, each terminating in an apex at its lower end and each of the baskets in the other rows being tapered toward its upper end and having a conical portion at its lower end terminating in an apex at its bottom.

NORMAN E. MACLEAN.
